UNITED STATES PATENT OFFICE

133,804

DESIGN FOR A SHOE OR SIMILAR ARTICLE

Abraham Gerber, Haverhill, Mass.

Application January 16, 1942, Serial No. 105,245

Term of patent 3½ years

To all whom it may concern:

Be it known that I, Abraham Gerber, a citizen of the United States, residing at Haverhill, in the county of Essex and State of Massachusetts, have invented a new, original, and ornamental Design for a Shoe or Similar Article, of which the following is a specification, reference being had to the accompanying drawing, forming part thereof.

Figure 1 is a side elevation of a shoe or similar article showing my new design.

Figure 2 is a top plan view of the same.

My design for a shoe as shown is character-

ized by the arrangement of strippings over shields, on inside and outside of vamp, and the arrangement of strippings on vamp and instep resulting in the formation of straps at instep. The strippings or vamp run from toe opening to opposite open shank and strippings forming straps run across from one side over instep to opposite sides to and across vamp, approximately midway from toe opening to open shank.

I claim:

The ornamental design for a shoe or similar article, as shown and described.

ABRAHAM GERBER.
